[57] CLAIM

The ornamental design for a transom screw cover for outboard motor, as shown and described.

DESCRIPTION

FIG. 1 is a perspective view of a transom screw cover for outboard motor showing my new design;

FIG. 2 is a front elevational view;

FIG. 3 is a top plan view;

FIG. 4 is a right side elevational view;

FIG. 5 is a left side elevational view;

FIG. 6 is a bottom plan view;

FIG. 7 is a rear elevational view; and,

FIG. 8 is a perspective view shown in a position of use, the broken line showing of a transom mounting bracket is for illustrative purposes only and forms no part of the claimed design.
